UNITED STATES PATENT OFFICE.

CLARENCE M. WILLIS AND AUGUST MORTENSEN, OF SAN FRANCISCO, CALIFORNIA,
ASSIGNORS TO THE FRISCO MFG. CO. INC., OF SAN FRANCISCO, CALIFORNIA.

BASS-DRUM SUPPORT.

Application filed May 26, 1925. Serial No. 32,941.

Our invention relates more particularly to a novel supporting stand for a bass drum, a playing mechanism being readily attached thereto and detached therefrom.

5 The general object of our invention is to provide a device for the indicated purpose, improved in various particulars, whereby to possess distinctive characteristics and advantages.

10 The invention further comprises a novel form of spur attachment to the drum, whereby the drum will be properly braced in operative position, as well as adjustments of the parts for use on drums of various sizes.

15 A still further object is to provide a bass drum supporting device which will not mar the instrument supported thereon.

With the above and other objects in view 20 the invention resides in the particular combination and arrangements of parts to be hereinafter more fully described illustrated and claimed, it being also an object to provide a device which is simple in construction, durable and efficient in operation and not likely to get out of order; and to afford a complete understanding of the same, reference being had to the accompanying drawings, in which—

25 Fig. 1 is a side elevation of one of the drum spurs and of one of the supporting link members associated with a drum hoop clamping device, the latter being partly in fragment;

30 Fig. 2 is a view in front elevation, also showing the drum partly broken away and with the supporting link attachments applied thereto;

35 Fig. 3 is a top plan view in section of the horizontal bar member illustrated in Fig. 2, showing the link securing means thereon and illustrating the manner of detachably connecting drum operating means to bolt stems, laterally extending from said bar member;

40 Fig. 4 is a side elevational view of a bass drum, showing the drum partly broken away and a spur attachment and the cooperating link construction applied thereto;

45 Fig. 5 is a plan view of one of the link members showing a series of radial indentations thereon;

50 Fig. 6 is a fragmentary end view of a drum operating mechanism, illustrating the

manner of attaching the same to the drum 55 supporting device; and

Fig. 7 is a view of a fragment of the bar member showing the indentations provided at the end thereof.

Similar characters refer to similar views 60 throughout the several views.

In a practical embodiment of our invention the bass drum support preferably consists of metallic spur attachments cooperating with a drum hoop clamping device and 65 provide means to prevent a shifting movement when a musician is operating the instrument. The front part of the support is provided with a vertically disposed bar member having laterally extending bolt 70 stems to which an instrument playing mechanism is removably attached.

Referring now more specifically to the drawings, a bass drum of the usual or any preferred construction having heads 11, 75 a cylindrical shell 12 at the edges of which hoops 13 are disposed, while rods 14 connect the outer edges of the hoops and sustain the shell for the purpose of tightening the heads thereon in the usual manner. In 80 order to hold the drum firmly in an upright position, spurs are provided for cooperation and attachment to the drum hoops 13, on the opposite side of the drum at points on each side near the floor line. 85

These spurs which we believe to be novel are constructed as follows. An interiorly screw-threaded hook embodying member 15 having a hook member 16 for engaging one of the drum hoops 13, has formed integral 90 thereon, adjacent to, and in a transverse relation to said hook 16, a boss 17 provided with a screw-threaded bore. A rod member 18 having one end thereof spur pointed as at 19 and the opposite end thereof provided 95 with a winged top 20, is intermittently screw-threaded as at 21 to correspond with the screw-threaded bore of the boss 17 by which it is carried. Owing to the fact that the rod member 18 is not threaded for some 100 spaced distance as indicated by 22, a rapid retraction of the rod member 18, through the boss 17, is made possible, after disengagement of the threaded part thereof from the boss 17, and a few additional reverse turns of the rod member 18, by means of the winged top 20, engaging the remaining threaded part 21 of the rod, will thus re-

tract the pointed end 19 thereof within the boss 17, eliminating any danger, which may result from coming in contact with the pointed spur end, also reducing the danger of its being injured when not in operative use.

The clamping action to the hoops of the drum is created through the medium of a clamping rod 23, having a handle of conventional form, designated by 24. The other end of said clamping rod being screw-threaded as at 25 to correspond with the interiorly screw-threaded hook member 15 and cooperating therewith in a clamping action. A hook embodying member 26 in the form of a sleeve, having a hook member 27 integral therewith for engagement with a drum hoop, said hook member 27 being disposed in an opposite direction relative to the direction of the hook member 16. This hook embodying member has a sliding fit upon said clamping rod and is associated therewith preferably near the said handle 24. Said hook members 16 and 17 respectively cooperating with said clamping rod 23 in operative clamping engagement on the drum hoops 13, as illustrated more clearly in Figs. 1 and 4 respectively.

A horizontally disposed bar member 28, 30 is pivotally connected at each end thereof, as at 29, to upwardly directed link members 30 by means of a bolt and nut construction 31. The bar member 28, being provided with a series of radial indentations 32, as shown on a bar fragment on Fig. 7, and to secure the link members 30 in different positions of adjustment against shifting, these link members are provided with a series of radial indentations 33 projecting upwardly therefrom as shown on Fig. 5, and adapted to register with the indentations provided on the ends of the bar member 28. The opposite ends of said link members are pivotally mounted as at 34 upon the clamping rods 23 exterior to the hook embodying member 26 and adjacent to the handle member 24 by means of an opening 35 provided on said links, and are held secured in this position by means of the clamping action hereinbefore described.

These spur points when clamped to the drum hoops at the rear of the drum, with the herein described linked bar member construction, positioned at the front of the drum, 55 form a tripod whereby the drum is firmly supported. Adjustments of inclination of the drum to the vertical line as indicated in Fig. 4, is effected by extending or by retracting respectively, the spur pointed members 19 by means of said winged top 20. A great advantage of this construction as shown in Fig. 4, is, that when the clamping device is applied to the drum, the spur point itself, being a part of the drum supporting device, does not come in contact

with the hoops or with the body of the drum and therefore cannot mar or injure the hoops or the drum.

Reverting to the horizontally disposed bar member 28, the said bar member is provided with a plurality of apertures 36 in spaced relation to each other. Interchangeable bolt stems 37, are provided with an outer head 38 forming an abutment, extending laterally from said bar member and are secured within said apertures 36 by means of nuts 39, as illustrated on Figs. 2 and 3 respectively.

This construction is designed to detachably support one or more drum operating mechanisms thereon. As indicated on Fig. 6 by a fragmental view, the end 40 of a drum operating mechanism is provided with openings 41, corresponding with the apertures 36 provided in the bar member 28, to receive and secure therein said short bolt stems 37, as shown on Figs. 3 and 6 respectively. Thus a drum operating mechanism will be placed in juxtaposition to the drum support and to the drum in a most convenient position to facilitate the operation or playing of the instrument.

From the foregoing description, taken in connection with the accompanying drawings, it is thought that the construction and operation of the invention will be clearly understood, and therefore, a more extended explanation is omitted.

We would state in conclusion that while the illustrated example constitutes a practical embodiment of our invention, we do not limit ourselves strictly to the mechanical details herein illustrated, since manifestly the same can be considerably varied without departure from the spirit of the invention as defined in the appended claim.

What we claim as new is:

The combination of a drum supporting and a drum operating means securing mechanism, comprising drum hoops hook embodying gripping members, rod members providing means for clamping said hook members upon the drum hoops in a spaced relation to each other, a boss formed integrally on the hook members positioned on the far side of the drum, in transverse relation thereto, being provided with a threaded bore, intermittently threaded rod members threaded into said bores, a spur point formed at the outer ends of said rods, the opposite ends thereof provided with adjusting means to advance or to retract the same relative to the drum hoops, a horizontally disposed bar member, upstanding link members pivotally secured to the ends of said bar, the opposite ends thereof interposed on said clamping rod members, adjacent to its operating means on the near side of the drum, said horizontal bar member having a plurality of transversely disposed

apertures formed therein to form receiving spaces for laterally extending headed bolt stems for detachably engaging drum beating instrumentalities, said spur points, located at the far side of the drum, cooperating with said link members to maintain a drum in an upright position and prevent

any shifting movement of the drum while being operated.

In testimony whereof we have affixed our ¹⁰ signatures.

CLARENCE M. WILLIS.
AUGUST MORTENSEN.
